US00D395741S

United States Patent [19]
Hatfield et al.

[11] **Patent Number:** **Des. 395,741**
[45] **Date of Patent:** ****Jul. 7, 1998**

[54] **PORTION OF A BOTTOM SURFACE OF A SHOE OUTSOLE**

D. 324,941 3/1992 Hatfield .
D. 378,871 4/1997 Hatfield D2/953

[75] Inventors: **Tinker Linn Hatfield**, Portland; **Mark J. Smith**, Beaverton, both of Oreg.

Primary Examiner—Celia Murphy
Attorney, Agent, or Firm—Banner & Witcoff, Ltd.

[73] Assignee: **Nike, Inc.**, Beaverton, Oreg.

[57] **CLAIM**

[**] Term: **14 Years**

The ornamental design for a portion of a bottom surface of a shoe outsole, as shown and described.

[21] Appl. No.: **65,760**

DESCRIPTION

[22] Filed: **Jan. 30, 1998**

FIG. 1 is a perspective view of a portion of a bottom surface of a shoe outsole showing our new design; and.

[51] **LOC (6) Cl.** **02-04**

FIG. 2 is a bottom plan view of the portion of a bottom surface of a shoe outsole shown in FIG. 1.

[52] **U.S. Cl.** **D2/953; D2/960**

The broken line showing of the herringbone pattern in the forefoot region, the circle in the forefoot, and the herringbone pattern in the rearfoot regions, and the remainder of the shoe sole is for illustrative purposes only and forms no part of the claimed design.

[58] **Field of Search** ..... **D2/897, 902, 906, D2/908, 914, 916, 919, 946-960, 962, 964; D12/147; 36/85, 101, 103, 104, 106, 113-115, 124, 126, 127-130, 3 B, 11.5, 12-15, 22 R, 25 R, 30 R, 32 R, 32 A, 33, 172**
